TOILET DISINFECTOR

Filed March 6, 1944

UNITED STATES PATENT OFFICE

2,424,174

TOILET DISINFECTOR

Joseph M. Jensen, Oakland, and Baldwin Vale,
San Francisco, Calif.

Application March 6, 1944, Serial No. 525,298

2 Claims. (Cl. 4—225)

1

This invention relates to disinfectors and more particularly to the method and means for applying measured quantities of liquid disinfectants drop by drop, to the surface of standing water in toilet bowls and the like.

With the above function in view, among the objects of the invention is the provision of a self contained hermetically sealed container for liquid disinfectants that may be unsealed and installed with the minimum of effort by the user.

Another object is the adaptation of the invention for use in mosquito abatement districts for automatically applying oily films to pools of stagnant water.

Water standing in toilet bowls, urinals and other toilet facilities becomes contaminated and contributes to the spread of disease by flying and crawling insects using it as a thirst quencher. The same is true of stagnant water in the open, where mosquitoes and other disease spreading life propagate. These dangers to life and health can be eliminated by a thin film of disinfectant floating on the surface of the water. In human habitations incidental bad odors can be neutralized by appropriate deodorants added to the disinfectant.

An advantage of the present invention is its simplicity and low cost of production. No separate container for the disinfectant is required because the whole apparatus can be discarded and replaced more cheaply and easily than to provide refills. However this is provided for in the larger units where a considerable number of sanitary units are served by a common disinfector.

When emptied the disinfector assembly is cheap enough to be discarded, if fabricated from relatively inexpensive plastics.

In this specification and the accompanying drawings the invention is disclosed in its preferred form. But it is to be understood that it is not limited to this form because it may be embodied in modifications within the spirit of the invention, as defined in the claims following the description.

In the one sheet of drawings:

Fig. 1 is a vertical section of a disinfector constructed and installed in accordance with this invention.

Fig. 2 is a plan view of the same from below.

Fig. 3 is a modified form adaptable to the larger units permitting the refilling of the reservoir and for outdoor use.

Fig. 4 is a view similar to Fig. 2, showing a modified form of mounting clamp.

2

In detail the construction illustrated in the drawings, referring first to Fig. 1, comprises the base 1, having the annular flange 2, and the nipple 3, preferably formed integrally therewith.

5 Diametrically opposite the nipple, the segmental socket 4 is formed in the bottom of the base. The cylindrical head 5 of the clamp fits snugly into the socket 4 and has the radial jaws 6, 7 protruding therefrom into opposed relation to the 10 nipple 3 to form therewith a three jawed resilient clamp projecting below the base 1.

The nipple 3 extends downwardly into the overflow pipe X, and the jaws 6 and 7 engage its outer periphery to securely hold the base 1 above the 15 top of this pipe. The lower edges of the jaws are formed at an angle to the horizontal plane of the base to insure the correct positioning of the base on the overflow pipe, by preventing its application in any other manner.

20 The tube 8 extends through and is cemented into the nipple 3 and projects above and below the base 1. The lower end of this tube is hermetically sealed by dipping it in a solvent and pinching the end of the tube, as at 8'.

25 The wick 9, preferably composed of a length of absorbent paper, such as filter paper or paper towel stock, extends the full length of the tube 8, protruding above its upper end and is bent 30 back so that its end approximates contact with the top of the base 1.

The upper end of the tube 8 and the protruding wick portion are enclosed within the cylindrical cap 10, the open end of which contacts the 35 top of the base surrounding the tube. The lower end of this cap has a small notch therein at 11, adjacent the protruding end of the wick.

The reservoir cup 12 has its open end fitted 40 snugly around the periphery of the base 1 abutting the flange 2 and is hermetically sealed thereto by an interposed solvent or cement. The top 13 of the cup 12 bears against the top of the cap 10 and forces it against the top surface of the base.

45 Before assembling the reservoir cup 12, it is filled with the desired disinfectant D. The base 1 is then inverted and inserted into the open end of the cup and sealed thereto. The assembly is then packed in a suitable container ready for marketing.

50 The invention operates substantially as follows: The disinfector is held upside down and the lower end of the tube 8 is snipped off with scissors or a knife, and inserted within the overflow 55 pipe X until the clamp formed by the nipple 3

and the jaws 6, 7 engage the upper periphery of the pipe, as described.

In this position the upper protruding end of the wick, saturated with the disinfectant D entering the notch 11, begins to function, drawing the disinfectant out of the reservoir 12 and spilling it drop by drop down the overflow pipe from the lower, severed end of the tube 8.

The overflow pipe X is the conventional toilet tank assembly, and discharges directly into the toilet bowl, on top of the residual water supplied to the bowl by the auxiliary supply pipe Z, after the tank flushing is completed.

In mosquito abatement districts where it is desired to coat the surface of stagnant water with medicaments, a supporting stake 14 can be inserted into the socket 4 and thrust into the bottom of the pool or streams feeding into the pool, see Fig. 3.

In the larger units and permanent installations, a filler cap 15 such as shown in Fig. 3 can be provided for refilling the reservoir 12.

The flow of disinfectant can be increased by increasing the size or capacity of the wick 9 or the notch 11. Another alternative for increasing the flow of heavy viscous oils, would be to provide a small vent hole such as 10' through the upper portion of the cap 10 to break the air-lock above the liquid in the reservoir 12.

The modified form of clamp shown in Fig. 4 consists of two projecting pins 6x, 7x, in opposed relation to the nipple 3 and adapted to engage the periphery of the pipe X in a manner similar to the jaws 6, 7. The design of the invention is susceptible to modifications to meet the type of plastics used and manner of molding, injecting or otherwise forming the base 1, and other parts of the assembly. For instance the base 1, clamp 3—6—7 and tube 8, may be formed integrally. The cap 10 and reservoir 12 may be similarly formed in one piece.

Having thus described this invention, what is claimed and desired to secure by Letters Patent is:

5 1. A disinfecter comprising a closed reservoir containing a fluid and having a nipple extending below the base of said reservoir; a pair of jaws on said base in juxtaposition to said nipple and cooperating therewith to form a clamp for mounting said base on the end of a pipe into which said nipple is extended; a tube having one of its ends sealed and its open end portion extending through said nipple and terminating near the top of said reservoir; and a wick extending upwardly in said reservoir and downwardly within said tube.

10 2. A disinfecter comprising a closed reservoir containing a fluid and having a nipple extending below the base of said reservoir; means on said base in juxtaposition to said nipple and cooperating therewith to form a clamp for mounting said base on the end of a pipe into which said nipple is extended; a tube having one of its ends sealed and its open end portion extending through said nipple and terminating near the top of said reservoir; and a wick extending upwardly in said reservoir and downwardly within said tube.
